(57) **CLAIM**

The ornamental design for a stylus pen, as shown and described.

DESCRIPTION

FIG. 1 is a front top perspective view of a stylus pen, showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear bottom perspective view thereof;

FIG. 9 is an enlarged view of the stylus pen in FIG. 6, shown separately for clarity of illustration;

FIG. 10 is an enlarged view of the stylus pen in FIG. 7, shown separately for clarity of illustration;

FIG. 11 is an enlarged view of the encircled portion '11' in FIG. 8;

FIG. 12 is an enlarged view of the encircled portion '12' in FIG. 8;

FIG. 13 is another perspective view of the stylus pen, shown with environment; and,

FIG. 14 is another front bottom perspective of the stylus pen in FIG. 8 with a top portion at the end of the stylus pen in an extended position.

The short dash-dash broken lines in FIG. 13 depict environment that form no part of the claimed design. The dot-dot-dash broken lines in FIGS. 8, 11, and 12, encircling enlargement portions of the claimed design form no part of the claimed design.
